DESIGN FOR A TEXTILE FABRIC TRIMMING

Julius Sobie, Louis Kaufman, and Solomon Graff,
New York, N. Y.

Application November 6, 1933, Serial No. 49,660

Term of patent 3½ years

To all whom it may concern:

Be it known that we, JULIUS SOBIE, LOUIS KAUFMAN, and SOLOMON GRAFF, citizens of the United States, and residing, respectively, at 555 Eighth Avenue, New York, in the county of Manhattan and State of New York; 555 Eighth Avenue, New York, in the county of Manhattan and State of New York; and 1730 Eastburne Avenue, New York, in the county of Bronx and State of New York, have invented a new, original, and ornamental Design for Textile Fabric Trimming, of which the following is a specification, reference being had to the accompanying drawing, forming part thereof.

Figure 1 is a plan view of a piece of fabric, showing a repeat unit of our new design contained be-

tween the parallel vertical and horizontal lines as shown.

Figure 2 is a sectional view taken between the pleated elements shown in Figure 1.

The characteristic feature of our new design resides in the effect caused by trimming a piece of textile fabric with invisible stitched pleated embroidered fabric.

We claim:

The ornamental design for a textile fabric trimming, as shown and described.

SOLOMON GRAFF.
LOUIS KAUFMAN.
JULIUS SOBIE.
